DERRICK MOUNTING FOR PORTABLE
DRILLING AND SERVICING RIGSJames Moon, Altadena, Calif., assignor to Western
Oil Tool & Engineering Co., Inc., Hollydale,
Calif., a corporation of California

Application June 28, 1948, Serial No. 35,666

5 Claims. (Cl. 189—11)

1

Portable drilling and servicing rigs are commonly employed in petroleum production for the drilling and servicing of wells. Such rigs are usually transported on trucks or trailers which carry a mast or derrick which may be positioned on the truck and erected on the drilling site. These masts are usually composed of one or more sections, usually two, in such form that the upper section may be telescoped into the lower section. When the derrick is to be transported it is collapsed onto the truck or trailer. Upon erection of the lower section, by rotation of this section about a hinge point on the truck, the telescoped hinge section may be withdrawn or extended from the lower section to give a mast or derrick of desired height.

Prior art construction of this type of rig is illustrated by the White Patent No. 2,204,713. In such construction the derrick, in its rest position upon the truck, is positioned with its upper end, that is, the end carrying the crown block, over the forward end of the truck, and the bottom legs of the derrick, that is, the portion which is positioned on the ground, protrudes beyond the end of the truck. The derrick, in such construction, in order to be erected, must be pivoted about a hinge point which is positioned beyond the end of the truck. This is provided by means of a truss mounted on the end of the truck and the derrick is hinged upon said truss with the hinge point beyond the end of the truck. The erecting mechanism consists of a link which is connected near the bottom end of the derrick and in this fashion the erecting mechanism pulls on the end of the derrick and rotates the derrick about the hinge point.

Realizing that the derrick may weigh as much as 9 to 10 thousand pounds and that the hinge point is several feet rearward of the rear axle and the end of the derrick is beyond that, it will be noted that when the derrick starts to erect a lever load of considerable magnitude is exerted about the rear axle and that the only counter-vailing force is the weight of the truck itself. For this reason it has been found necessary in the construction of the prior art, as a measure of safety, to anchor the front of the truck before starting to erect the derrick.

It is also necessary to accurately spot the truck before starting to erect the derrick. In order to spot the truck the truck must be backed into position. Since the derrick is erected from the rear end of the truck, this becomes an extremely difficult and hazardous procedure. It is also a time consuming procedure since it is possible that

2

the spotting may not be accurate and this cannot be told until the derrick is erected and the truck has been tied down to permit the erection of the derrick. The derrick must then be retracted, the truck unanchored and resotted, by backing to and fro, i. e., jockeying into position.

I have designed a derrick mounting for such trucks which avoids these difficulties. I have designed a derrick mounting which permits the truck to be moved into position head first so that the driver can see where he is going and so accurately spot his truck and accurately position the derrick in the desired position. This I have accomplished by mounting the derrick so that its bottom end, that is, the bottom legs, protrudes beyond the cab while the top of the derrick, that is the crown block end, is toward the rear of the truck.

As an additional feature of my invention I mount the derrick upon a pivot point which is forward of the front axle and over the cab. I also mount the erecting mechanism so that the reactive thrust imposed, when the derrick is lifted off its rest position and rotated about its pivot point, is directed to the rear of the front axle but in front of the rear axle. As a result of this arrangement, the reactive thrust and the static load imposed on opposite sides of the front axle are in balanced arrangement, thus imposing no tilting force about any of the axles of the truck.

The driver in his cab position, where he has, as is conventional in trucks, all of the steering and driving controls, can see the derrick moving into position at all times and thus may, if he so desires, readjust his position with great facility. Because of the fact that the cab is positioned adjacent the front wheels, where also the derrick is provided, the driver has an unobstructed view of the location where the derrick is to be erected. The improved visibility imparts a surer control by the driver who is in control of the lifting mechanism.

These and other objects of my invention will appear more clearly from the following description taken together with the drawing, in which:

Fig. 1 is a side view of the truck, partly schematic, showing the position of the derrick in rest position and in partly erected position in dotted line;

Fig. 2 is a plan view of Fig. 1 with the parts removed for clearer illustration;

Fig. 3 is a fragmentary detail, partly broken away, of the front end of the truck with the derrick shown in erected position;

Fig. 4 is a front view of Fig. 3;

- Fig. 5 is a section taken along 5—5 of Fig. 3;
 Fig. 6 is a view partly in section with parts broken away taken along 6—6 of Fig. 2;
 Fig. 7 is a section taken along line 7—7 of Fig. 6;
 Fig. 8 is a section taken along line 8—8 of Fig. 6;
 Fig. 9 is a section taken along line 9—9 of Fig. 8;
 Fig. 10 is a section taken along line 10—10 of Fig. 6;
 Fig. 11 is a section taken along line 11—11 of Fig. 6; and
 Fig. 12 is a section taken along line 12—12 of Fig. 6.

The truck 1 has an enclosed body 2. Slots 3, for purposes to be described below, are provided in the top cover. The truck carries its main motive power as an engine positioned in the rear of the truck in engine 4 compartment 5. The truck carries, enclosed in the body, winches 6 and 7 and suitable power transmitting mechanism, change speed mechanism, controls, etc. It has rear wheels 8 and front wheels 9 and a cab 10 which is positioned at the forward end of the truck. In the cab 10 are positioned the steering controls and the motive power controls, as is conventional in truck design. The chassis is composed of a longitudinal frame member 11 and rear cross member 12 and front cross member 13, positioned midway under the cab and in front of the forward front wheels 9.

Mounted upon the front cross member 13 and within the cab 10 are two columns 14 positioned one on each side of the cab. These carry a cross member 15 positioned underneath the roof of the cab. Two bearings 16 are positioned through the roof of the cab upon the member 15. The bearings 16 are each split and composed of two halves 21 and 22 hinged at 23 and bolted together with bolt 24. Pivoted inside the bearings 16 is the tubular cross member 17 of the lower section 18 of the derrick 19. The upper end of the lower section 18 rests upon support 20 positioned beyond the rear wheels just in front of the motor compartment 5. It will be observed that the ends of the derrick terminate in legs 25a which protrude beyond the cab. The distance between the ends of legs 25a and the pivot point 17 is somewhat less than the vertical distance from the pivot to the ground so that when the derrick is erected the legs can swing into position, as will be further described. The hydraulic jack cylinders 27 are pivoted at 25 upon a bracket 26 mounted on the longitudinal frame member 11 just rearward of the front axle. The ends of extensible piston 28 of the jack is connected to a split bearing composed of sections 29 and 30 which are locked in place by the clamping bolt 32. The tubular cross member 33 which connects the rear legs 34 (see Fig. 5) of the lower section 18 is journalled in the split bearing 29. It will be observed that there are two such units (see Figs. 6 and 10), one positioned on each side of the truck body, each mounted upon the longitudinal member 11, and operating one in each of the slots 3 (see Figs. 2 and 10).

The jack 28 is hingedly mounted at 27 upon pins 27" on the longitudinal members 11 and beneath the brackets 26. The jack 28 has an extensible foot member 35 mounted upon the threaded leg 36 which passes through the jack head member 37 through a screw-thread connection. The member 36 ends in a ball and socket joint 38 to which it is connected at the foot 35.

The member 37 is connected by a link 39 which is pivotally connected at 40 to the underneath side of the longitudinal main frame member 11 by a removable pivot pin.

When the derrick is being transported it is in the retracted position shown in Fig. 1 with the top end of the lower section 18 resting upon the supports 20. The jack 28 is in its dotted position (Fig. 6). The link 39 is disconnected from the member 11, by removing the pin 40, and swung into the dotted position as shown, and the leg 36 screwed into the tube of the jack 28". The jack 28" is locked into the dotted position by a strap or some other means not shown and as will be understood by those skilled in the art. There is one such jack on each side of the truck as shown in Fig. 10.

The truck may be driven into the derrick site. It will be observed that the driver has full view of the site and can spot his truck accurately. It will be observed that no equipment associated with the truck is positioned in front of the driver. Particularly, as will be seen, the derrick legs straddle the cab, and the derrick, while it is being erected or retracted to rest position, does not obstruct the view of the operator of the cab. When it is in this position jacks 28" are moved into position shown in Figs. 6 and 10 and the link 39 connected at the pivot 40 at each jack.

The foot 35 of each jack is contacted against the ground by rotating the jack legs 36, thus wedging the truck in position.

The jack 27 is then extended, the derrick rotating off its cradle on supports 20 and pivoting around the pivot 17 into vertical position, as shown in Figs. 3 and 4. When the derrick is in vertical position the legs 41 are screwed down until they rest in position upon blocks 42 suitably provided.

It will be observed that in moving into position from its rest position to its vertical position the thrust load imposed by 28 is exerted against bracket 26 and against the ground through jack 28" while the static load imposed upon the pivot 17 is transmitted through the column 14 to the cross members 13 and longitudinal member 11 and to the front axle. The load on 13 acts with the load on 26 to produce a bending moment in the longitudinal frame member 11 between these points, which bending load is transmitted to the axle and to the ground. Since the load on 26 is carried on the member 11 between the rear and front axles and its moment is added to the weight of the truck and is greater than the moment of the static load on 13, there is no tendency of the truck to tip and a stable platform for the drilling derrick is presented even without the aid of the jack 28".

It will also be observed that should it become necessary when it appears that the derrick is not moving into its proper position it may be possible, even though this is not desirable, to retract the leg 36 or not to employ the jack 28" at all at this stage and jockey the truck into proper position with the derrick partly erected or retracted as desired. This is because the driver can see at all times where his derrick is going from his position in the cab and because a stable platform for the tilting derrick is presented.

While I have described a particular embodiment of my invention for the purpose of illustration, it should be understood that various modifications and adaptations thereof may be made within the spirit of the invention as set forth in the appended claims.

I claim:

1. A portable derrick, comprising a chassis, front wheels mounted on an axle positioned adjacent the front end of the chassis, rear wheels mounted on an axle positioned adjacent the rear end of the chassis, a driver's position with steering and motive power controls positioned adjacent the front end of said chassis and extending forward of the front axle, a collapsible and extensible derrick pivotally mounted on the chassis to move from a rest position on said chassis with the top end of the derrick positioned rearwardly of said chassis and the bottom of said derrick being positioned on said chassis toward the front end of said chassis, spaced two front and two rear legs for said derrick, cross bracing between said legs with a free area between a portion of the rear legs, said derrick comprising a lower section and an upper section, means for moving said upper section relative to said lower section to extend and to collapse said derrick, a hinge on said derrick positioned near the bottom end of said derrick, said hinge also positioned on said chassis intermediate the forwardmost limits of said chassis and the front axle and above said driver's position, and means for rotating said derrick about said hinge to an erect position adjacent the front end of said chassis, said means including a rotation power transmitting member connected to said derrick at a point on said derrick spaced from said hinge, said transmitting member transmitting rotative power to said derrick to rotate said derrick about said hinge, and a load transmitting connection between said member and said chassis, said connection being positioned on said chassis between said front and rear axles, lower portions of said legs being spaced apart transversely with respect to said chassis a distance greater than the transverse extent of said driver's position, and said lower leg portions and said hinge being located with respect to the longitudinal axis of said chassis to cause a portion of the driver's position to enter said free area and the lower rear leg portions to straddle said driver's position when the derrick is in said erect position.

2. A portable derrick, comprising a chassis, front wheels mounted on an axle positioned adjacent the front end of the chassis, rear wheels mounted on an axle positioned adjacent the rear end of the chassis, a driver's position with steering and motive power controls positioned adjacent the front end of said chassis, a collapsible and extensible derrick pivotally mounted on the chassis to move from a rest position on said chassis with the top end of the derrick positioned rearwardly of said chassis and the lower end of said derrick being positioned on said chassis toward the front end of said chassis, spaced two front and two rear legs for said derrick, cross bracing between said legs, said derrick comprising a lower section and an upper section, means for moving said upper section relative to said lower section to extend and to collapse said derrick, a hinge on said derrick positioned adjacent the lower end of said derrick, said hinge also positioned on said chassis intermediate the forwardmost limits of said chassis and the front axle and above said driver's position, and means for rotating said derrick about said hinge to an erect position adjacent the front end of said chassis with the lower end of said derrick legs in load transference relation to the ground, said means including a rotation power transmitting member connected to said derrick at a point on said derrick spaced from said hinge, said trans-

mitting member transmitting rotative power to said derrick to rotate said derrick about said hinge, and a load transmitting connection between said member and said chassis, said connection being positioned on said chassis between said front and rear axles, the portions of said legs in load transference relationship to the ground being spaced apart transversely with respect to said chassis a distance greater than the transverse extent of said driver's position, and said leg portions and said hinge being positioned with respect to the longitudinal axis of said chassis locating said driver's position between the said leg portions with the said leg portions straddling said driver's position when the derrick is in said erect position.

3. A portable derrick, comprising a chassis, front wheels mounted on an axle positioned adjacent the front end of the chassis, rear wheels mounted on an axle positioned adjacent the rear end of the chassis, a driver's position with steering and motive power controls positioned adjacent the front end of said chassis, a motive power unit positioned on said chassis rearward of said driver's position, winches positioned on said chassis rearward of said driver's position, a derrick pivotally mounted on the chassis to move from a rest position on said chassis with the top end of the derrick positioned rearward of said chassis behind said cab, the bottom of said derrick being positioned on said chassis toward the front end of said chassis, a hinge on said derrick positioned near the bottom end of said derrick, said hinge also positioned on said chassis intermediate the forwardmost limits of said chassis and said front axle and above said driver's position, and means for rotating said derrick about said hinge to an erect position adjacent the front end of said chassis, said derrick including spaced two front leg members and two rear leg members, cross bracing between said leg members, said derrick legs being in load transference relationship to the ground when said derrick is in erect position, the derrick axis being positioned in a slant plane with respect to the perpendicular as to cause the axis of said derrick to bear away from said chassis at an acute angle to the vertical when said derrick is in an erect position, portions of said derrick supporting legs resting on and in load transference relationship to the ground when the derrick is in erect position being spaced apart transversely with respect to said chassis a distance greater than the transverse extent of the forwardmost portion of said chassis, and leg portions and said hinge being positioned with respect to the longitudinal axis of said chassis locating the portion of said legs in said load transference relationship to the ground below said forwardmost portion of said chassis with said last-named leg portions straddling said driver's position when the derrick is in erect position.

4. A portable derrick, comprising a chassis, front wheels mounted on an axle positioned adjacent the front end of the chassis, rear wheels mounted on an axle positioned adjacent the rear end of the chassis, a driver's position with steering and motive power controls positioned adjacent the front end of said chassis, a motive power unit positioned at the rear end of said chassis, a winch positioned between said motive power unit and the driver's position, a collapsible and extensible derrick pivotally mounted on the chassis to move from a rest position on said chassis above said motive power unit and said winch with the top end of the derrick positioned rearwardly of said

chassis and the bottom of said derrick being positioned on said chassis toward the front end of said chassis, spaced two front and two rear legs for said derrick, cross bracing between said legs, said derrick comprising a lower section and an upper section, means for moving said upper section relative to said lower section to extend and to collapse said derrick, a hinge on said derrick positioned adjacent the lower end of said derrick, a hinge support positioned on said chassis adjacent the front axle and supporting said hinge above said driver's position, said motive power unit and said winch, and means for rotating said derrick about said hinge to an erect position adjacent the front end of said chassis, said means including a rotation power transmitting member connected to said derrick at a point on said derrick spaced from said hinge, said transmitting member transmitting rotative power to said derrick to rotate said derrick about said hinge, and a load transmitting connection between said member and said chassis, said connection being positioned on said chassis between said front and rear axles, said derrick legs being in load transference relation to the ground when said derrick is in an erect position, portions of said legs which are resting on the ground when the derrick is in an erect position being spaced apart transversely with respect to said chassis a distance greater than the transverse extent of said driver's position, and said leg portions and said hinge being located with respect to the longitudinal axis of said chassis causing a portion of the driver's position to be positioned between the said leg portions, said leg portions extending from said hinge to rest on the ground and straddle said driver's position with the derrick in said erect position with the hinged derrick in load transference relationship to the ground.

5. A portable derrick, comprising a chassis, 40 front wheels mounted on an axle positioned adjacent the front end of the chassis, rear wheels mounted on an axle positioned adjacent the rear end of the chassis, a driver's position with steering and motive power controls positioned adjacent the front end of said chassis, a motive power unit positioned at the rear of said chassis, a collapsible and extensible derrick pivotally mounted on the chassis to move from a rest position on said chassis with the top end of the derrick posi-
